OTHER PUBLICATIONS

Jiang, L., "Pen Cap," U.S. Appl. No. 291437,378, filed Nov. 15, 2012.

Primary Examiner — Elizabeth Albert(74) *Attorney, Agent, or Firm* — Christensen O'Connor Johnson Kindness PLLC(57) **CLAIM**

The ornamental design for a marker, as shown and described.

DESCRIPTION

FIG. 1 is a top front perspective view of a marker showing my new design;

FIG. 2 is a left side elevation view thereof;

FIG. 3 is a front elevation view thereof, with the rear elevation view being a mirror image of the front elevation view;

FIG. 4 is a right side elevation view thereof;

FIG. 5 is a top plan view thereof; and,

FIG. 6 is a bottom plan view thereof.

The surfaces depicted in broken lines in FIG. 6 are included to show portions of the marker that form no part of the claimed design.
